JAR CAP

Henry Z. Gora, Bridgeport, Conn., assignor to
 Jenkins Bros., New York, N. Y., a corporation of
 New Jersey

Application January 31, 1941, Serial No. 376,895

2 Claims. (Cl. 215—43)

This invention relates to closures or caps for jars, particularly Mason fruit jars or the like such as are commonly used by home canners, and yet more particularly to a closure or cap as characterized which is of the one-piece type.

Heretofore, caps for fruit jars of the character under discussion have been provided with a flaring rim having a rigid seating surface for engagement with a sealing gasket that is backed by a shoulder on the jar. Seating surfaces of this character frequently have irregular seating widths by reason of the nonuniformity of the flaring rim arising from the manner in which these caps are conventionally formed. Furthermore, it has been demonstrated that, particularly when the sealing rings are of poor quality, they have a tendency to shrink or warp because of temperature and moisture changes, age or the like, with the result that an airtight closure is not maintained due to the rigidity of the cap construction.

It is an object of this invention to provide a cap of the character referred to which overcomes the foregoing difficulties.

More particularly it is an object of this invention to provide a cap of the type characterized which includes automatic compensating means whereby the desired airtight closure is maintained after the initial sealing notwithstanding changes in the gasket.

Another object of this invention is to provide a cap of the type characterized that assures uniformity of seating contact with the gasket.

Another object of this invention is to provide a cap of the type characterized with resilient means which may be readily tensioned in making the initial sealing contact and which will assure the maintenance of the sealing contact with the gasket notwithstanding subsequent changes in the gasket.

Another object of this invention is to provide a cap of the type characterized which provides a contact between the cap and the gasket of minimum radial extent so as to assure a tight closure with the least amount of effort.

Another object of this invention is to provide a cap as last characterized which also includes automatically operating means to assure the maintenance of the airtight closure.

Other objects will appear as the description of the invention proceeds.

The invention is capable of receiving a variety of mechanical expressions, one of which is illustrated on the accompanying drawing, but it is to be expressly understood that the drawing is for

purposes of illustration only and is not to be construed as a definition of the invention, reference being had to the appended claims for that purpose.

5 The accompanying drawing illustrates somewhat diagrammatically and on an enlarged scale an embodiment of the present invention in transverse section:

As shown, 10 designates a jar of any suitable size, construction and material, such as the conventional Mason fruit jar commonly used by home canners, and provided with the usual shouldered portion 11 and helical rib 12 to form a thread for securing a cap thereto. The shoulder 11 is adapted to receive the usual jar ring or sealing gasket 13 of rubber or any other suitable material for effecting an airtight closure as hereinafter explained.

In accordance with the present invention the 20 cap or closure member 14 is made, in one piece, of any suitable material and of such thickness as to provide the necessary rigidity. The peripheral flange 15 may be knurled as indicated at 16 to facilitate manipulation of the cap, and 25 said flange is provided with a threaded portion 17 for cooperation with the thread 12 on the neck of the jar. Unlike the standard construction of caps of this character, which merge into a flared edge or rim to provide a seating surface for engagement with the gasket 13, the cap of the present invention is provided with a bead 18 which is U-shaped in cross section so as to simulate the corrugation of a bellows. The depth and width of said bead 18 may be varied, depending in part on the thickness and material of which the cap is composed, but taking into consideration such material and thickness the bead 18 should be of sufficient depth and width so as to possess appreciable resilience for a purpose to be explained. Said bead 18 is disposed between the end of the thread 17 and the edge 19, and said edge is preferably made of reinforced construction. To reduce the radial extent of contact between the edge and the gasket 30 35 40

45 and at the same time to maintain a substantially uniform contact throughout the periphery of the cap, said edge is preferably formed by curling the edge of the rim as shown on the drawing so that it will simulate a wire of approximately three sixty-fourths of an inch in diameter. While a circular bead at the rim edge is preferred, this is not essential as the curled edge may be given other cross sections within the contemplation of the present invention.

When a cap constructed in accordance with the

present invention is applied to the neck of a jar, after a gasket has been disposed as illustrated, tightening of the cap places the U-shaped bead 18 under an initial tension. The tensioned bead thereafter acts as an automatic compensating means so that if the gasket 13 shrinks or warps with lapse of time the tension in the bead 18 causes the edge 19 to follow the receding gasket and maintain a substantially uniform airtight closure therewith. As the cross-sectional contour of the edge is such as to establish an approximately line contact between the edge and the gasket, the initial sealing contact may be effected with a minimum of exertion. Also the contact is substantially uniform throughout its peripheral extent. Thus by firmly tightening the cap against the gasket the resilient bead 18 is placed under an initial tension, and thereafter the airtight closure is automatically maintained notwithstanding shrinking or warpage of the gasket.

It will therefore be perceived that by the present invention a one-piece cap of improved construction is provided whereby airtight contact with the gasket is maintained. The sealing contact may be established with minimum effort, irregularities in the engagement between the cap and the gasket are minimized and, owing to the action of the automatic compensating means

provided by the bead 18, uniform air sealing contact is thereafter automatically continued.

While the embodiment of the invention illustrated on the drawing has been described with considerable particularity it is to be expressly understood that the invention is not limited thereto, as changes may be made in the details of construction, proportion, size, etc., without departing from the spirit of this invention. Reference is therefore to be had to the appended claims for a definition of the invention.

What is claimed is:

1. A one-piece cap or closure for jars including a peripheral threaded flange having a U-shaped bellows-like corrugation between the threaded portion and the edge of the flange which is compressed by the application of the cap to the jar and which automatically expands to maintain a sealing contact between the edge thereof and an opposed surface engaged if the latter shrinks or warps.

2. A one-piece cap or closure for jars including a peripheral threaded flange having a curled edge to provide an approximately line contact with an opposed surface and a resilient corrugation between the threaded portion and said curled edge compressed by the engagement of said edge with an opposed surface.

HENRY Z. GORA.
